UNITED STATES PATENT OFFICE.

CYRUS R. FUREY, OF LOGANSPORT, INDIANA, ASSIGNOR OF ONE-HALF TO
JOHN H. KORNMANN, OF SAME PLACE.

ALARM MAIL-BOX.

SPECIFICATION forming part of Letters Patent No. 611,573, dated September 27, 1898.

Application filed August 21, 1897. Serial No. 649,020. (No model.)

To all whom it may concern:

Be it known that I, CYRUS R. FUREY, a citizen of the United States, residing at Logansport, in the county of Cass and State of Indiana, have invented a new and useful Alarm Mail-Box, of which the following is a specification.

My invention is an improvement in the class of "drop" mail-boxes which are adapted for private use and ordinarily attached to doors or door-jambs of private residences. It is more particularly an improvement in such as are provided with a gong or alarm attachment adapted to be operated when the lid of the box is opened.

The invention is embodied in the construction, arrangement, and combination of parts hereinafter described.

The invention is illustrated in the accompanying drawings, in which—

Figure 1 is a vertical sectional view of the mechanism, taken on the line *a a*, Fig. 4. Fig. 2 is taken on line *a a*, Fig. 4, and it differs from the previous figure by the lid being partly raised. Fig. 3 is a vertical sectional view taken on the line *b b*, Fig. 4. Fig. 4 is a longitudinal sectional view taken on the line *c c*, Fig. 1. Fig. 5 is a detail view of the wheel 10. Fig. 6 is a detail view of the gong 11.

Similar letters and numbers refer to similar parts throughout the several views.

The box or casing A has a lid 31, the said lid having a pivotal connection to the box at E. The said box has adjacent to the top a lateral extension or projection B, Fig. 4. The said extension or projection B is, with the exception of the top 24, of a rectangular shape and is used as a receptacle for the gong 11 and as a sounding-box. The gong is secured in a permanent manner and free from contact with the surrounding mechanism by being bolted to the shaft 21 at 22, which in turn is bolted to the plate 18 at 22^a. The plate 18 has a semicircular offset at 22^a—that is to say, a lateral curve or bend which projects into the box extension B, as shown. The said plate is secured to the side C of the box A by the bolts 26, 37, and 39^a, and the plate 18 is so located as to permit the semicircular offset and the attached gong 11 to extend or set into the sounding-box D. That the gong

11 and the semicircular offset may extend into the sounding-box an opening 27 has been made through the side C of the box A.

A wheel 10 is located on the shaft 21 at 28, 55 and the said wheel has a pivotal connection thereto. The wheel 10 is provided with projections or catches 29, which are to move the spring 12 when the said wheel 10 is put in motion.

To communicate motion to the wheel 10 or to make the spring operative, a connection-bar 14 is provided which has pivotal connections with the wheel 10 at 30 and the lid 31 at 32. When the lid 31 is raised, the connection-bar 14, acting in conjunction with said lid, communicates motion to the wheel 10.

As the wheel moves the projections or catches 29 are brought in contact with the spring 12 at 34. As wheel 10 continues to move the said spring is forced away from its resting position at 35 until the catch 29 releases it by passing beyond the end 36. When the spring 12 is released, the clapper 13, which has a permanent connection to said spring, strikes the gong 11. The strokes are repeated 65 as often as a catch 29 releases the spring, the number of strokes varying from two to three in number.

The wheel 10 is provided with a stop-pin *e*, which when the said wheel makes a return 80 movement comes in contact with the spring 12, and thereby preventing the crank-pin *h* from stopping on a dead-center or to the side *i* of the center line *rr*. To further facilitate the operation of the said wheel 10, a stop 50 is 85 provided which is bolted at 26 to the plate 18. The stop 50 has the shape of an angle-iron. When the lid 31 is raised to the position where it will stand perpendicular, the connection-bar 14 will come in contact with 90 the stop 50, thereby marking the distance of travel by the crank-pin *h*.

It is evident that without the above stops the wheel 10 would be inoperative.

The projections or catches 29 of the wheel 95 10 have concave and convex sides. The concave side engages with the spring 12 and prevents a release of the said spring until the catch 29 passes the end 36 of the said spring. When the lid 31 is lowered, the convex side 100 of the catch 29 engages with the spring 12, and the spring slides over the convex side of

the catch and passes it. The clapper 13, with extension-spring 52, is soldered to the spring 12 at 53.

That the spring 12 may be properly adapted 5 to come in contact with the projections of the wheel 10 and strike the gong 11 this is arranged by passing the said spring around the bolt 39^a and the end 40 partly around bolt-head 37. To prevent the spring 12 from working too far away from surface of the plate 18, a quadrant 41 is placed at 42, which is suitably adapted for the purpose described.

To protect the operation of the above or previously-described mechanism from contact 15 with the mail deposited, a wire screen 43 is placed at 44, which not only separates the mail from the mechanism previously described, but allows a larger volume of sound to come from the gong 11, which otherwise 20 could not be secured.

The projections or catches 29 are cast in the wheel 10.

A supplemental letter-box 47, Fig. 3, is arranged within the box A and attached to a 25 side wall of the latter at a point near its top. This box 47 is open at the top and designed and adapted for the reception of letters or other small mail-packages. It thus subserves a highly-useful purpose, since it holds letters 30 deposited in it at a point where they are conveniently accessible from the top of the main box A and saves the trouble of reaching to the bottom of the latter and there groping for letters. It also occupies so small a space 35 as to constitute no serious obstruction to use of the remainder of the chamber of box A for the reception of newspapers and other large mail-packages. It will be further seen that by

the arrangement of the gong in the lateral box B and the wheel 10 alongside and parallel to it 40 they occupy small space and leave the main chamber or compartment free for reception of mail-matter.

What I claim is—

1. The improved alarm mail-box comprising 45 the body A, having the lateral extension or sounding-box B, the gong located in such extension, the wheel 10 arranged facing and close to said gong, and provided with a series of curved teeth, the spring 12 having its free 50 end arranged for contact with the teeth and provided with a clapper adapted to strike the gong, the hinged box-lid, and a rod connecting it with that side of the wheel toward which its teeth are curved, as shown and described, to operate as specified.

2. The improved alarm mail-box, comprising 55 the body A, having a hinged lid, and the lateral extension or side chamber, the bar attached to its side and curved laterally into 60 such chamber, the gong attached to and supported by said bar, a spring secured alongside the bar and projecting upward beside the wheel, a clapper projecting from the spring into striking proximity to said gong, a 65 toothed wheel journaled on or extending from the gong-support, and arranged vertically adjacent to the gong, and the connecting-rod pivoted to the lid and to the side of the wheel toward which the teeth of the latter curve, as 70 shown and described.

CYRUS R. FUREY.
